UNITED STATES PATENT OFFICE.

WALTER A. SHEWHART, OF BROOKLYN, NEW YORK, ASSIGNOR TO WESTERN ELECTRIC COMPANY, INCORPORATED, OF NEW YORK, N. Y., A CORPORATION OF NEW YORK.

SOUNDPROOF SHIELD.

1,365,425.

Specification of Letters Patent. Patented Jan. 11, 1921.

Application filed December 26, 1919. Serial No. 347,414.

To all whom it may concern:

Be it known that I, WALTER A. SHEWHART, a citizen of the United States, residing at Brooklyn, in the county of Kings and 5 State of New York, have invented certain new and useful Improvements in Sound-proof Shields, of which the following is a full, clear, concise, and exact description.

This invention relates to sound-proof 10 shields for telephone receiving instruments.

Shields for use in sound-proofing telephone instruments of the type used in head sets have heretofore existed in two general forms, neither of which has proven sufficient 15 effective for employment in situations where outside noises tend to interfere with the use of the telephone instruments. One of these forms has comprised a cup of rubber in which the receiver was mounted, the 20 walls of the cup being relatively thin and presenting its edge to the head of the wearer in a comparatively perpendicular position. This type of cup has proven wholly ineffective for use in such trying situations as are 25 found in airplane work where engine and wind noises are extremely hard to overcome. This has been due both to the inadequately thick walls of the cup member and to the 30 unsubstantial, relatively narrow and correspondingly ineffective seal provided between the edge of the cup and the operator's head, which failed to prevent extraneous noises 35 from reaching the interior of the shield. The other form has consisted of a comparatively thick-walled cup member formed of soft rubber and which also presented its 40 edge to the head of the wearer in a comparatively perpendicular relation thereto. This form, while providing a greater degree 45 of effectiveness than that of the thin-walled cup previously referred to, was still inadequate for the purpose in that the blunt and comparatively resistant edge of the cup would not yield or collapse to the required 50 extent to faithfully follow the contour of the wearer's head and thereby provide an effective seal. It is the object of the present invention to provide a soundproof shield in which the objections referred to are overcome and which will provide an efficient 55 sound-excluding seal with the head of the wearer.

The invention consists in the provision of a cup member formed of soft rubber having a flaring and thinly tapering feather

edge which, as has been repeatedly demonstrated in practice, will provide a wide and effective seal when pressed to the head of the operator. The invention also consists in the provision of a shield cup member 60 formed of relatively thick sponge rubber having its edge formed to fit the irregular contour of an operator's head, and the use of this form of cup in combination with the cup having the thinly tapering edge. 65

In the drawings, Figure 1 is a view in perspective of a telephone head set including soundproof receiver shields embodying the invention; and Fig. 2 is an enlarged view partly in elevation, and partly in section, of one of the sound-proof devices shown in Fig. 1.

In the drawing, a cap member 1 is shown to which are attached elastic receiver supporting bands 2 and 3 which wholly encircle 75 the head of the operator and cross each other substantially at right angles adjacent the operator's ears and support seats 4 to which the receivers are attached.

In order to shield the receivers from the 80 effect of extraneous noises a cup member 5 is provided which is preferably formed of soft rubber, this material having as a characteristic the power of preventing the passage therethrough of sounds of low frequency, such as engine noises or the roaring sound of rushing wind in airplane work. An important feature of the invention resides in the thin feather edge 6 with which the cup member is provided, the thinly 85 tapering edge having a widely flared formation which produces a wide area of contact between the flat under surface of the edge and the head of the operator. The thin feather edge referred to yields readily under pressure and is easily collapsed to bring about a close contact of the thin edge with every portion of the irregular contour of the surface to which the cup is pressed. Not only is a close contact secured, but a sealing 90 border of substantial width is achieved that is very effective in excluding noise. 95

To additionally insure the exclusion of extraneous noises from the receiver 7 I may provide the inner cup member 8, preferably 105 formed of thick sponge rubber and having its edge formed to engage the operator's head in a substantially perpendicular relation, as indicated in Fig. 2. The edge of the cup member 8 is formed to fit the contour 110

of the wearer's head and for that purpose is provided with a depression 9 designed to fit the projecting posterior portion of the operator's jaw underneath the ear.

5 It will be seen that in addition to the seal provided by the contact of the two cup members with the operator's head, the spaced apart relation of the edges of the cup members forms an air chamber 10 which itself 10 tends to obstruct the passage of outside noises into the interior of the protecting shield.

What is claimed is:

1. A soundproof shield for a telephone receiver consisting of a cup member formed of soft rubber and having a thin feather edge.

2. A sound-proof shield for a telephone receiver consisting of a thick-walled cup member formed of soft rubber and having a thinly tapering feather edge.

3. A sound-proof shield for telephone receivers consisting of a cup member formed of soft rubber and having a thinly tapering 25 widely flaring edge.

4. A sound-proof shield for telephone receivers consisting of an inner cup member

formed of soft rubber, and an outer cup member formed of soft rubber and having a thin feather edge spaced from the edge of 30 said inner cup member.

5. A sound-proof shield for a telephone receiver consisting of an inner cup member formed of sponge rubber having its edge presented perpendicularly to the operator's head, and an outer cup member formed of soft rubber and having a flaring edge presenting a flat surface to the head of the 35 wearer.

6. A sound-proof shield for a telephone receiver consisting of an inner cup member formed of sponge rubber having its edge presented perpendicularly to and formed to fit the contour of the operator's head, and an outer cup member formed of soft rubber 40 and having a thinly tapering widely flaring edge spaced from the edge of said inner cup member and presenting a flat surface to the head of the wearer.

In witness whereof, I hereunto subscribe 50 my name this 23rd day of December, A. D., 1919.

WALTER A. SHEWHART.
